UNITED STATES PATENT OFFICE.

EMIL GATHMANN, OF SOUTH BETHLEHEM, PENNSYLVANIA, ASSIGNOR
TO BETHLEHEM STEEL COMPANY, OF SOUTH BETHLEHEM, PENNSYLVANIA, A CORPORATION OF PENNSYLVANIA.

PROJECTILE.

No. 796,993.

Specification of Letters Patent.

Patented Aug. 15, 1905.

Application filed January 6, 1904. Serial No. 187,958.

To all whom it may concern:

Be it known that I, EMIL GATHMANN, a citizen of the United States, residing at South Bethlehem, in the county of Northampton and State of Pennsylvania, have invented certain new and useful Improvements in Projectiles, of which the following is a specification.

My invention relates to that class of projectiles provided with soft-metal caps; and it consists in the means of securing and retaining the said caps in place upon the projectiles, as fully set forth hereinafter and as illustrated in the accompanying drawings, in which—

Figure 1 is a side view of a projectile with the cap in cross-section thereon, showing the improved retaining means. Fig. 2 is the same, showing the form of the cap before it is secured and the die for securing the same. Fig. 3 is a detached view of the retainer, and Fig. 4 is a detached sectional view showing the form of the cap before it is secured in place.

The projectile is of any suitable construction, with a body portion A and a pointed end which, as shown, is conoidal, and adjacent to the said end is an annular recess 1, extending circumferentially and of a suitable cross-section to coincide with the cross-sectional form of a retainer C, the latter being in the form of a divided ring, the inner portion of which fits the said recess. The soft-metal point B has a socket adapted to receive the pointed end of the projectile and has also an annular recess of a form corresponding to the projecting portion of the retaining-ring C, the cap extending back beyond the said ring and fitting close against the surface of the projectile, as shown in Fig. 1, whereby the said ring serves as a means of securely retaining the cap upon the point of the projectile.

In the application of the cap to the projectile the cap is first formed with a socket and an annular enlargement 3, Fig. 4, of such internal dimensions that it will pass readily over the retaining-ring and externally greater in diameter than the body of the cap. The parts are put in position, Fig. 2, and the cap is then passed through the opening of a die D and, together with the projectile, is carried onward until the action of the die serves to

compress the enlargement of the cap, bringing it to the same diameter as the remaining portion of the cap and extending and spreading the projection 3 over and around the retaining-ring and onto the face of the projectile.

Preferably the retainer is of hard metal—as, for instance, hard steel—so that the annular projection or lip of the cap will readily flow over the same during the passage of the cap through the die. Further, the ring is preferably split, so that it can be expanded to pass it over the point of the projectile and into the groove or recess and will then contract, so as to fit closely the said groove.

When the cap is applied, it wholly incloses the ring and holds the ends together, so that they cannot separate and permit the cap to become loose.

It will be evident that the ring may be of any suitable cross-sectional form, the grooves in the projectile and cap corresponding thereto, and that it may be made of any desired material.

Without limiting myself to the construction and arrangement shown, I claim—

1. A projectile having a pointed end, combined with a soft-metal cap having a socket receiving said end, and with an annular retainer fitting an annular groove in the projectile and corresponding groove in the cap and wholly inclosed by the latter, substantially as set forth.

2. A projectile having a pointed end combined with a soft-metal cap having a socket receiving said end, and with an annular retainer of harder material than the projectile, fitting an annular groove in the projectile and corresponding groove in the cap and wholly inclosed by the latter, substantially as set forth.

3. A projectile having a pointed end and annular groove adjacent to the end, combined with a cap of soft metal having a socket receiving the end of the projectile, and an annular groove coinciding with that of the projectile, and a retainer consisting of a split ring fitting and inclosed in said grooves, substantially as set forth.

4. A projectile having a pointed end and annular groove adjacent to the end combined

with a cap of soft metal having a socket receiving the end of the projectile and an annular groove coinciding with that of the projectile, and a retainer consisting of a split ring of harder metal than the projectile fitting and inclosed in said grooves, substantially as set forth.

In testimony whereof I have signed my name to this specification in the presence of two subscribing witnesses.

EMIL GATHMANN.
